ABSTRACT OF THE DISCLOSURE

Radiation counter tube including elements with a work function of 3.5 electron-volts at operating temperature and separators having a TK-100 minimum of 475° C. and an envelope of 54% SiO₂, 18.5% Al₂O₃, 13.5% CaO, 8% BaO and 6% ZnO.

The present invention relates to gaseous discharge counter tubes operating at high temperatures and used for registering radioactive radiation.

There are known gaseous discharge counter tubes operating in the range of positive temperatures up to 200° C.

An object of the present invention is to provide a radioactive radiation counter which is able to operate at high temperatures of the order of 200 to 350° C. and over, said counter having improved electrical characteristics and longer service life as compared with the known ones.

This object is achieved by the fact the design components of the counter are made of materials having a work function of at least 3.5 electron-volts at the operating temperature and the inner separating elements having TK-100 not less than 475° C. (where TK-100 is the temperature at which the resistivity of materials is equal to 10⁸ ohms/cm.). As one of the materials meeting the above mentioned requirements, there is preferably used glass of the following composition: SiO₂—54%; Al₂O₃—18.5%; CaO—13.5%; BaO—8%; ZnO—6%.

In particular, the invention makes it possible to perform logging works in deeper high-temperature wells as well as to create counting equipment without an auxiliary cooling system. This enables to considerably simplify the counting and measuring equipment, to decrease its overall dimensions, weight and power consumption.

The invention will further be described in connection with an exemplary embodiment thereof.

The accompanying drawing is a cross-sectional view of a counter tube of the invention.

The counter comprises gas-filled envelope 1, anode 2, cathode 3, field-forming tube 4, internal lead-out of stem

2

5 and spring 6 serving for keeping tense the anode filament.

The inner separating elements and the envelope of the counter are made of glass having TK-100 not less than 475° C., and containing no alkali metals or their oxides in its composition, featuring low electric conductivity at high temperatures and enabling the degassing of the housing and all the design elements of the counter at elevated temperatures up to 700° C.

An exemplary composition of glass is as noted above:

	Percent
SiO ₂	54
Al ₂ O ₃	18.5
CaO	13.5
15 BaO	8
ZnO	6

The melting point of the glass is 820° C. The linear expansion coefficient is equal to $(49 \pm 2) \times 10^{-7}$ deg. ⁻¹.

What is claimed is:

1. A radioactive radiation counter tube comprising in operative association elements of material having a work function of at least 3.5 electron-volts at operating temperature, separating elements having a TK-100 minimum of 475° C., and an envelope housing said elements, said separating elements and envelope being of glass having, at 200° C. and higher, a work function of at least 3.5 electron-volts and a TK-100 of at least 475° C., said glass being of about the following composition:

	Percent
SiO ₂	54
Al ₂ O ₃	18.5
CaO	13.5
20 BaO	8
ZnO	6

2. A radioactive radiation counter tube comprising in operative association elements of material having a work function of at least 3.5 electron-volts at operating temperature, separating elements having a TK-100 minimum of 475° C., and an envelope housing said elements, said separating elements and envelope being of glass having, at 200° C. and higher, a work function of at least 3.5 electron-volts and a TK-100 of at least 475° C.
